UNITED STATES PATENT OFFICE.

JOSEPH HENRY FALLOWS, OF BLACKBURN, ENGLAND.

SPINDLE-DRIVING ARRANGEMENT FOR SPINNING, DOUBLING, AND TWISTING MACHINES FOR YARNS AND THREADS OF FIBROUS SUBSTITUTES.

1,259,501.

Specification of Letters Patent. Patented Mar. 19, 1918.

Application filed September 20, 1917. Serial No. 192,375.

To all whom it may concern:

Be it known that I, JOSEPH HENRY FALLOWS, a subject of the King of Great Britain, residing at 3 Ewood, Blackburn, in the county of Lancaster, England, have invented certain new and useful Improvements Relating to Spindle-Driving Arrangements for Spinning, Doubling, and Twisting Machines for Yarns and Threads of Fibrous Substances, of which the following is the specification.

This invention relates to spinning, doubling and twisting yarns or threads of fibrous substances and to that type of apparatus in which a ring and traveler are mounted upon or carried by an independently driven tube, cylinder or its equivalent that is rotatably mounted on a stationary sleeve through which the spindle passes and 20 is driven by a whirl and driving band in any appropriate manner. The present invention has for its chief object to provide an improved form of compensating drive between the cylinders which rotate the spindles and the carriers.

In the accompanying drawings:—

Figure 1 is an end elevation and Fig. 2 a front elevation of part of a spinning frame provided with a compensating drive between the cylinders which rotate the spindles and the carriers.

A² indicates one of the carriers and C one of the spindles.

The spindles C and carriers A² may be 35 driven by bands from cylinders c¹, a¹⁷, in the known manner and an improved form of compensating drive from one cylinder to the other comprises a chain wheel a¹⁸ rigidly connected with the cylinder a¹⁷ and a chain 40 wheel c² rigidly connected with the cylinder c¹. The cylinder c¹ for driving the spindles C is carried at each end by a bearing d on a cross frame d¹ which connects the lifter rails D and supported in a bearing d² on one 45 cross frame above the chain wheel c² and to one side thereof is another chain wheel d³. Mounted below and to one side of this wheel on a stud which may be attached to some stationary part of the frame is another chain 50 wheel F. Above wheel F is a chain wheel F' for guiding the chain after leaving wheel F. Passing around these chain wheels

is an endless chain f which passes from the top cylinder chain wheel a¹⁸ to the bottom cylinder chain wheel c², under the latter, 55 over the chain wheel d³ that rises and falls therewith, then under the wheel F on the stationary stud and back to the upper cylinder chain wheel a¹⁸. By this arrangement during the lifting and lowering of the two 60 chain wheels d³, c² on the lifter rail frame d¹, one wheel gives off what the other wheel takes up and an even tension is maintained upon the chain during all positions of the bottom driving cylinder c¹. 65

What I claim as my invention and desire to secure by Letters Patent of the United States is:—

1. In apparatus for spinning, doubling, and twisting yarns or threads of fibrous substances, in which a spindle and carrier are driven from two separate cylinders, one of which can rise and fall, a pulley rigidly connected with each cylinder, a pulley arranged to rise and fall with the rising and falling 75 cylinder, a pulley mounted on a stationary bearing, a flexible driving connection passing from the top cylinder pulley to the bottom cylinder pulley, under the latter, over the pulley that rises and falls therewith, under 80 the pulley on the stationary stud and back to the upper cylinder pulley.

2. In apparatus for spinning, doubling, and twisting yarns or threads of fibrous substances, a carrier driving cylinder mounted 85 in stationary bearings, a spindle driving cylinder mounted in bearings in a cross frame connecting the lifter rails, a chain wheel rigidly fixed on each cylinder axle, a chain wheel rotatable on a stud carried by the cross 90 frame, a chain wheel rotatable on a stationary stud and a chain passing from the top cylinder chain wheel to the bottom cylinder chain wheel, under the latter, over the chain 95 wheel on the cross frame, under the chain wheel on the stationary stud and back to the upper cylinder chain wheel.

In testimony whereof I affix my signature in presence of two witnesses.

JOSEPH HENRY FALLOWS.

Witnesses:

CHRISTOPHER ISHERWOOD,
FREDERICK SPINK.
